[57] ABSTRACT

Multiple full bobbins simultaneously doffed from group to group from textile machines such as draw-twisters are automatically accommodated within a bobbin storing cage in prescribed arrangements without any undesirable mutual contact of the bobbins and the apparatus carrying the cage travels intermittently along the row of spindles in order to carry out the group doffing.

METHOD AND APPARATUS FOR DOFFING FULL BOBBINS ON TEXTILE MACHINES SUCH AS DRAW-TWISTER

The present invention relates to a method and apparatus for doffing full bobbins on textile machines such as draw-twisters.

Various types of doffing and donning systems have already been proposed in the field of the textile industry, especially in the field of the spinning industry. However, in most of the conventional systems, these operations are accompanied with indispensable surface contact of the bobbins with the other bobbins or surrounding machine elements. Such contact often causes undesirable damage of the yarns composing the bobbins.

In the case of bobbins of spun yarns composed of staple fibers, the weight of the bobbins is in a range from 0.3 to 0.5 kg, i.e. the bobbins are relatively light, and the yarns on the bobbins already have many surface fluffs which were raised in the preceding processes. In the case of this type of yarn, ill effects caused by the damage due to the abovementioned surface contact form less problems regarding the final quality of the yarn.

In contrast to this, in the case of the bobbins of yarns composed of synthetic filaments, the weight of the bobbins is in general in a range from 1.0 to 3.0 kg. Consequently, the weight of the bobbins cannot be neglected in this case in view of the damage caused by the surface contacts. Further, owing to the relatively low frictional property of such synthetic materials, the shape of the bobbins tends to be undesirably deformed by such surface contact of the bobbins during the doffing operation.

For these reasons, a technique, which requires special training is needed to successfully carry out the doffing operation of the bobbins made up of synthetic filamentary yarns. In addition, exacting manual labor is necessary to handle of the bobbins of such heavy structure. Because of such difficulties, the employment of an automatic doffing system for the bobbins made up of synthetic yarns has not been as well developed as in the case of the spun yarns.

The principal object of the present invention is to provide a method for doffing full bobbins automatically on textile machines such as draw-twisters without any surface contact of the bobbins with the other bobbins or surrounding machine parts.

The object of the present invention is to provide an automatic apparatus for carrying out the above-described doffing and/or donning operation very successfully.

In order to attain the above-described objects, in the doffing system of the present invention, multiple bobbins are simultaneously extracted off of spindles of the machine by a doffing mechanism. Bobbins so doffed are carried separated from each other from the row of the spindles by the receding movement of the doffing mechanism. The bobbins so conveyed away from the machine are transferred to poles of a bobbin transfer. This sequential operation may further be followed by accommodation of the bobbins within a bobbin storing mechanism, and disengagement of the poles from the full bobbins so accommodated.

Further features and advantages of the present invention will be clearer from the ensuing description, refer-

ence being made to the accompanying drawings, in which:

FIG. 1 is a partly sectional side plane view of the apparatus of the present invention;

FIG. 2 is a front plane view of the apparatus shown in FIG. 1;

FIGS. 3 to 12 are explanatory drawings for showing the sequential doffing operation according to the method of the present invention;

FIG. 13 is a side plane view of the bobbin transfer, used in the apparatus of the present invention;

FIG. 14 is a front plane view of a part of the arrangement shown in FIG. 13, i.e. full bobbin transfer, seen in the direction of the arrow Z;

FIG. 15 is a view seen in the direction of the arrows C-C in FIG. 14;

FIG. 16 is a front plane view of the pole used in the bobbin transfer;

FIG. 17 is a sectional plane view of the pole seen in the direction of the arrows F-F in FIG. 16;

FIG. 18 is a sectional plane view seen in the direction of the arrows A-A in FIG. 16;

FIG. 19 is a side plane view of the doffing mechanism;

FIG. 20 is a front plane view of the driving part for the connector of the bobbin transfer;

FIG. 21 is a partly sectional front plane view of the mechanism for causing the tilting motion of the full bobbin transfer;

FIG. 22 is a view seen in the direction of the arrow R in FIG. 21;

FIG. 23 is a sectional plane view taken along the line B-B in FIG. 21;

FIG. 24 is a perspective plane view of the bobbin storing mechanism used in the apparatus of the present invention;

FIG. 25 is a perspective plane view of the bobbin receiver used in the bobbin storing mechanism shown in FIG. 24;

FIG. 26 is an explanatory side plane view of the bobbin storing mechanism in combination with the bobbin taking-out mechanism;

FIG. 27 is a sectional plane view taken along the line A-A in FIG. 26;

FIG. 28 is a front plane view of the bobbin storing cage and its related machine parts;

FIG. 29 is a perspective plane view of the bobbin storing cage;

FIG. 30 is an explanatory view showing the mode of the bobbin accommodation within the bobbin storing cage;

FIG. 31 is a side plane view of the embodiment, wherein the gripper chucks are accompanied with nozzles for ejecting compressed air;

FIGS. 32A to 32C are explanatory drawings for showing the bobbin doffing operation when the guide is used, and;

FIG. 33 is an enlarged perspective plane view of the guide used in the system shown in FIGS. 32A to 32C.

Referring to FIGS. 1 and 2, a basic embodiment of the apparatus of the present invention is shown. In the illustrated arrangement, multiple spindles 73 are mounted on a spindle rail 75 fixed to a framework 74 of the draw-twister in equally spaced alignment. Each spindle is provided with a bobbin (not shown in the drawing) inserted over it. Yarns supplied from drawing

rollers 72 are wound over the corresponding bobbins while forming balloonings by the assistance of rings and travellers.

The present invention concerns automatic exchange of bobbins produced on the textile machine with the above-described structural and operational features. Namely, the apparatus of the present invention includes a framework 54 of a carriage movable along guide rails 62 which are disposed on the floor in front of the spindle rail 75. As is clearly seen in FIG. 2 a drive motor 65 is mounted on the framework 54 and a sprocket 63a, fixedly mounted on the output shaft of the motor 65, is connected with sprocket 63 via a chain 64. The sprocket 63 is fixedly mounted on the shaft of one of the wheels 60, through which the carriage is mounted on the guide rails 62. Travel of the carriage along the guide rails 62 is effectuated by the running of the motor 65. In order to adjust the travelling speed of the carriage and the travelling time program, the drive motor 65 is desirably accompanied with a suitable known type of electro-magnetic brake mechanism and reduction gear mechanism (not shown), which are joined therewith in series connections. Further, a doffing mechanism, an empty bobbin feed mechanism and bobbin transerrer mechanism, etc., are mounted over the upper face of the framework 54.

The doffing mechanism is mounted on a movable base 40 which is held horizontally by a plurality of sliders 45. These sliders 45 are slidably mounted on horizontal shafts 46 and 46a, which are fixedly mounted on the framework 54 via supporter brackets 44. In the case of the illustrated embodiment, the base 40 is so mounted on the shafts 46 and 46a via sliders 45 that it moves towards and away from the front side of the draw-twister.

This two-way movement of the movable base 40 is caused by the running of a drive motor 35, mounted on the base itself, in combination with a suitable electro-magnetic brake mechanism and reduction gear mechanism (not shown). For this purpose, a driver sprocket 78 is mounted fixedly on the output shaft of the motor 35. A drive shaft 77 is rotatably disposed to the lower side of the base 40 and is provided with a driven sprocket 42 fixedly mounted onto the middle part thereof. This driven sprocket 42 is connected for rotation with the driver sprocket 78 of the motor 35 via a chain 79. In this way, running of the motor 35 naturally causes corresponding rotation of the drive shaft 77. Pinions 41 are fixedly mounted on both ends of the drive shaft 77 in meshing engagement with racks 43 fixed on the upper face of the framework 54.

With this arrangement, when the output shaft of the motor 35 rotates counterclockwise in FIG. 1, these pinions 41 are rotated in the same direction and, thanks to the pinion-rack engagement, the base 40 is moved leftwards along the horizontal shafts 46 and 46a. On other other hand, when the output shaft of the motor rotates clockwise, the base 40 travels rightwards in the drawing along the shafts 46 and 46a.

A pair of brackets 39-1, for the doffing mechanism, are mounted on the movable base 40 being spaced from each other in the travelling direction of the carriage. As seen in FIG. 3, each bracket 39-1 is provided with a pair of swingable arms 29 and 30 pivoted thereto at their bottom ends. Free ends of the arms 29 and 30 are connected by a triangular link 32 so that the ends always keep a presecribed positional relationship to

each other. In the arrangement shown in FIG. 2, the triangular links 32 are connected on both sides to each other by a connecting rod 31, which extends in the carriage travelling direction and is received in the links 32 on both ends. The rod 31 is not axially turnable with respect to the links 32.

The connecting rod 31 is provided with multiple gripper chucks 36 of any known type, such as pneumatic, mechanical, electro-magnetic or oil-pressure type, mounted thereon at intervals corresponding to distances between neighbouring spindles 73. The purpose of these chucks 36 is the doffing of full bobbins from the spindles 73 by their strong grasp on the head parts of the bobbins on which the bobbins are built.

In order to effect the driving of the doffing mechanism of the above-described structure, the pivoted ends of both swingable arms 30 are rigidly connected to each other by a drive shaft 38 running almost parallel to the connecting rod 31. This drive shaft 38 is provided at its midpoint with a gear box 39-2, whose input shaft is connected to the output shaft of a drive motor 33 associated with a suitable reduction gear mechanism via a coupling assembly 37.

At the time of doffing the full bobbins on the spindles 73, the drive motor 33 is energized for running and the drive shaft 38 is turned thereby at a prescribed speed via the elements 37 and 39-2. By this turning of the shaft 38, the arms 29 and 30 are swung towards the draw-twister, i.e. counterclockwise in the arrangement shown in FIG. 1, so that the chucks 36 are brought into engagement with head parts of the full bobbins resting on the spindles 73. After the engagement is completed, compressed air is supplied to the chucks 36 from a compressor 34 mounted on the movable base 40 by the operation of a suitable electro-magnetic valve (not shown). Concurrently with this compressed air supply, the drive motor 33 starts running in the reverse direction. This induces the returning swing of the arms 29 and 30 to extract full bobbins 59a off of the spindles 73.

Detail structure and operation of the doffing mechanism included by the apparatus of the present invention will now be explained, referring to the illustrations given in FIGS. 13 to 15.

As shown in FIG. 13, a horizontal plate 44 is carried by main body 175 of the apparatus of the present invention. On this plate 144 both the doffing mechanism and the bobbin transfer mechanism are mounted. So that the bobbins 178 can be received in a storing mechanism 183 placed within the main body 175 when they tilt, the plate 144 is provided with cut-outs 176 and 145 at positions intersecting the paths of the tilting bobbins 178b. A horizontal shaft 158 is disposed over the plate 144 being carried by its both ends in bearing brackets 159 and 159a fixed on the plate surface. A pair of mutually spaced bearing brackets 157 and 157a are inserted over the horizontal shaft 158 in an axially slideable arrangement and a slide base 156 is carried by the two brackets so that the base 156 is slideable parallel to the shaft 158.

A drive motor 192 is mounted on the base 156 being accompanied with a suitable reduction mechanism in order to actuate the sliding movement of the slide base 156. In more detail, a sprocket 193 fixed on the output shaft of the drivemotor 192 is connected with a sprocket 155, the sprocket 155 being fixed on the middle of a shaft 138 which is supported

by bearing brackets 152 and 153 on the underside of the slide base 156. On both ends of the shaft 138 pinions 154 are provided which are in meshing engagement with stationary racks 174 fixed on the horizontal plate 144 by brackets 173 and 173a. Upon the running of the drive motor 192, the slide base 156 reciprocates along the horizontal shaft 158 relative to the main body 175.

In order to fix the terminations of the stroke of the reciprocal movement carried out by the slide base 156, a micro-switch 160 is secured to the underside of the base 156 in such an arrangement as to come in contact with clogs (not shown) disposed in suitably selected positions of the horizontal plate 144. By this contact of the micro-switch 160 with the clogs, the drive motor 192 is de-energized and an internally installed braking mechanism is made effective.

The doffing mechanism of the full bobbins 178 is arranged on the slide base 156 of the above-described structure. In the actual doffing operation on the draw-twister, the slide base 156 is firstly moved towards the spindles 179, being actuated by the drive motor 192. The movement is stopped when the end of the base 156 has arrived at the location Y in FIG. 13, and the doffing operation is initiated in this disposition.

When the bobbins 178 have been doffed to the position of the links 185b and 186b in FIG. 19, the slide base 156 recedes from the spindles 179 while maintaining the full bobbins 178f in the above-mentioned doffed disposition. This recession of the slide base 156 is actuated by the running of the drive motor 192 via the elements 193, 155, 150, 154 and 174. Further, this recession of the base 156 is stopped when the end of the base 156 arrives at the location X in FIG. 13, after travelling the stroke D.

In this disposition, the links 185b and 186b bring the bobbin 178d to the position shown with chain and dot lines in FIG. 13 by their tilting towards the spindles 179 and the bobbin is upheld in almost vertical disposition. A pole 101 is now inserted into the bobbin 178 in this disposition. Next the compressed air is discharged from air chucks 194 disposed on the triangular link 187 so that the bobbin 178 rests on a seat 107 of the pole 101. By this mounting of the bobbin 178 on the seat 107, the pole 101 automatically inclines towards the position designated as 101a in FIG. 13. This inclined condition is called first-staged tilting in the following description.

In order to successfully obviate the possible interference of the slide base 156 with the bobbin 178 in this first-staged tilting, the slide base 156 is provided with a rectangular cut-out 177 which is profiled in accordance with the locus of bobbin travelling. Taking this structure into consideration, it is desirable that the bearing brackets 157 and 157a are so disposed to the slide base 156 that they bear the load by the doffing mechanism on both sides of the cut-out 177.

The very characteristic feature of the apparatus of the present invention resides in the fact that the swingable arms 29 and 30, and the drive mechanism thereof, are mounted on the movable base 40 which is capable of approaching towards and receding away from the spindle rail 75. Through employment of this structure, the movable base 40 can be registered in advance at a position whereupon the gripper chucks 36 can readily catch the full bobbins resting on the spindles 73. This can be done by sensing the positions of the front end

of the spindle rail 75 or of the spindles 73, even when the guide rails 62 are incorrectly positioned relative to the framework 74 of the machine. The fact that the doffing mechanism is functioned to perform the horizontal movement is especially welcome in case of the travelling type autodoffer responsible for multiple sets of draw-twisters, resulting in easy construction or installation.

Another characteristic feature of the apparatus of the present invention resides in the structure of the swingable arms 29 and 30. That is, the arms 29 and 30 of different lengths are pivoted to different portions of the common bracket 39-1 and outer ends of the two arms 19 and 30 are kept at a constant distance from each other by the triangular link 32. By the combined effect of the swinging movements of the arms 29 and 30 with the turning movement of the triangular link 32, it is possible to freely design the doffing locus of desired form. Thanks to this freedom in the design of the doffing locus, it has become possible to eliminate the trouble in the conventional doffing operation, in which the bobbins leave the corresponding spindles too quickly just after they have been hoisted away from the spindles.

Next the structure and operation of the full bobbin transerrer will be explained. In the case of the present invention, it is most desirable that this full bobbin transerrer should be located under the movable base 40 carrying the doffing mechanism. The full bobbin transerrer is to be arranged so that it can reciprocate in directions opposite to the moving directions of the movable base 40. Therefore, there is no need of installing a separate driving source for this transerrer and, in the case of the present embodiment, the movement of the movable base 40 is transmitted to the transerrer via a suitable combination of pinion-rack mechanism in such a manner that the direction of the movement can be reversed.

As shown in FIGS. 1 and 2, poles 51 are transfer of the full bobbins are arranged in alignment at positions under and corresponding to the positions of the gripper chucks 36. The poles 51 are turnably mounted at their bases to a rod 52, which runs parallel to the row of the spindles 73, at intervals equal to the spacing between the neighbouring spindles 73. The positions of the poles 51 on the rod 52 correspond to the positions of the spindles 73 on the spindle rail 75. The boss 80 of the respective pole 51 is accompanied with a helical spring (not shown) so that the abutment of the boss 80 is placed in a pressure contact with the abutment of a stopper 53.

Next, the detailed structure and operational function of the above-described poles 51 will be explained in more detail, reference being made to FIGS. 16 to 18. The structure of the pole 101 must be designed in consideration of the requirement that, on one hand, it can fairly bear the weight loaded by the full bobbin and impact forces applied thereto during the operation in the first-staged tilting disposition. On the other hand, it must be of a light structure. Usually, the pole 101 is made by bending a steel band into U-shape. The pole 101 is internally reinforced by pins 102 and 102a and the bottom ends thereof are shaped obliquely by a face 106 parallel to the pin 102. The face 106 is in contact with the upper end of a boss 105 pressuredly inserted into the surface of the seat 107. Further, the pole 101 is turnable about a pin 103 fixed to the upper end of the

boss 105. A spring 104 is inserted over the pin 103 so as to make the pole 101 in axial coincidence with the boss 105. Due to this structure, the pole 101 can be bent in the direction of the arrow S in FIG. 17 when any suitable external force is applied thereto. A collar 108 is formed in one body with the seat 107 and the latter is turnable about a connector 110. Axial movement of the collar 108 along the connector 110 is restricted by a stopper 109 fixed to the connector 110 by a pin 111 and the projection 115 of a link 113 fixed to the connector 110 by a pin 112. Further, in order to reverse the collar 108 after the turning for the tilting, a helical spring 114 is disposed in between the collar 108 and the link 113. As shown in FIG. 17, the outer end of the helical spring 114 is fixed to a pin 120 formed on the side face of the seat 107 and the inner end thereof is fixed to a pin 121 formed on the outer peripheral face of the projection 115 of the link 113. Owing to the provision of this helical spring 114, the collar 108 is always urged to turn in the direction of the arrow S in FIG. 17. When no external force is operative on the arrangement, the cut-out surface 116 of the collar 108 is kept in contact with the cut-out surface of the stopper so that the pole 101 is kept upright on the connector 110.

The pole 101 of the above-described structure can be easily inserted into the lower part of the bobbin of the full bobbin 178 when the latter is placed almost upright after lowering of same by the links 185 and 186. For this purpose, the transverse cross section of the pole is designed very small. The full bobbin 178 so inserted over the pole 101 at first stands upright on the seat 107 of the pole 101 after being released from the grasp of the air chuck 194. However, because the upper face of the seat 107 is slightly inclined, the bobbin 178 immediately tilts in the counterclockwise direction in FIG. 17 and stands still in the disposition of the full bobbin 178a in FIG. 13. In order to effect this stopping of the turning of the bobbin 178, the stopper 109 is securely mounted onto the connector 110.

The structure relating to the stopper 109 will now be described in detail referring to the illustration in FIG. 18. When the collar 108 turns in the clockwise direction overcoming the spring force by the spring 114 due to the weight of the full bobbin 178 mounted thereon, the cut-out surfaces 116 of the collar 108 and the stopper 109 disengage from each other and the other cut-out surface 117 of the collar 108 turns clockwise. At the moment when the cut-out surface 117 of the collar 108 comes into pressure contact with a cushion rubber 118 disposed to the other cut-out surface of the stopper 109, turning of the collar 108 stops. In this disposition, both the pole 101 and the full bobbin 178 are placed in the positions designated with 101a and 178a in FIG. 13. In this way, the full bobbins 178 carried by the multiple poles 101 are simultaneously moved horizontally to the positions designated as 178b in the drawing. This horizontal movement of the full bobbins 178 takes place before the full bobbins 178 are received in the storing mechanism 183 of the main body 175 while keeping the tilting condition.

Structure and operation of the mechanism for causing this horizontal movement of the connector 110 will now be explained in detail, reference being made to the illustrations in FIGS. 13 to 15. It has already been explained that, in the case of the present embodiment, the horizontal movement of the connector 110 finds its

driving source in the horizontal movement of the slide base 156. In the drawing, racks 162 are fixed to both sides of the underside face of the slide base 156. These racks 162 are attached by brackets 161 and 161a so as to run in directions parallel to the direction of the horizontal shaft 158. A shaft 165 is horizontally carried by bearing brackets 164 and 168 on the horizontal plate 144, and a pinion 163 is carried by the shaft 165 in a meshing engagement with the rack 162. Further, a gear 167 is rotatably mounted onto the middle of the shaft 165 and an electro-magnetic clutch 166 is disposed near the gear 167 in order to cancel the connection between the shaft 165 and the gear 167. Detailed structure of this part is illustrated in FIG. 20, in which the shaft 165 is driven for rotation by the rack 162 of the slide base 156 via the pinion 163. A rotor 166a of the electro-magnetic clutch 166 is fixed to the middle of the shaft 165 by a key 1100 and an electro-magnet 166b is coupled with the rotor 166a via a bearing. The electro-magnet 166 is kept stationary being fixed to the horizontal plate 144 via a foot 199. Splines 1101 are formed on the peripheral surface of the boss part of the gear 167 mounted for free rotation on the shaft 165. The disc of the electro-magnet 166b is slidably inserted over the splined part of the gear. In the above-described arrangement, when electric voltage is applied to the electro-magnet 166, the disc of the magnet 166b is attracted by the rotor 166a of the clutch 166 and, therefore, the rotation of the shaft 165 is transmitted to the gear 167 via the disc of the magnet 166b. When the application of the electric voltage is stopped the disc is disconnected from the rotor 166a and, therefore, the rotation of the shaft 165 is not transmitted to the gear 167. A rack 170 is carried by bearing brackets 169 and 169a in a slideable arrangement in the direction the same as the axial direction of the horizontal shaft 158 and in meshing engagement with the gear 167. One end of the above-described connector 110 is linked to an arm 125, which is a part of the rack 170, via a bracket 126 as shown in FIG. 15. By this arrangement, the horizontal movement of the slide base 156 can induce the corresponding horizontal movement of the connector 110 but in the opposite directions. An assembly quite the same as the above-described one is disposed to the other projection defining the cut-out of the horizontal plate 144 and the other end of the connector 110 is linked to this assembly. By this structure, the connector 110 can be slid in the axial direction, i.e. the direction shown with the arrow S in FIG. 15. The connector 110 is linked at right angle to the racks 170 on both ends thereof. Horizontal movement of the connector 110 is caused by the rotation of the gear 167.

The operational sequence of the above-described bobbin transerrer is as follows. In the first place, the bobbin 178 transferred onto the pole 101 on the connector 110 tilts into an almost horizontal disposition designated by 178a due to its own weight. Next, the slide base 156 slides over the distance D from the position X to the position Y in FIG. 13. This movement of the slide base 156 is transmitted to the connector 110 via the elements 162, 163, 165, 166 and 170. Therefore, the bobbin 178 is moved in the direction opposite to the moving direction of the slide base 156. In this operation, the upper end of the bobbin 178 is positioned sufficiently lower than the underside face of the slide base 156 and the movement of the bobbin 178 is

not hindered by the cut-out 177 of the slide base 156. During the movement of the slide base 156, the connector 110 moves over the distance E until the axis thereof comes just above the axis of a sprocket 182 of the storing mechanism 183 in FIG. 13. At this very moment, a micro-switch (not shown) is actuated so that the electric current to the electro-magnetic clutch 166 is stopped and, thereby, the transmission of the movement of the slide base 156 to the connector 110 is cancelled. Because of this cancellation of the movement of the connector 110 immediately stops at that position and, thereby, the full bobbin 178 is held stationary at the position designated by 178b.

This stoppage of the connector 110 is electrically sensed and the electric signal so produced is brought into solenoids 122 disposed on the brackets 126 simultaneously so as to momentarily cancel the restriction on the rotation of the connector 110. By this cancellation of the restriction on the rotation, the weight of the full bobbin 178b forces the connector 110 to turn to the position of the second-staged tilting. By this turning, the full bobbin 178b is placed on corresponding bobbin receivers 180 and 180a in a horizontal disposition. This disposition is designated by 178c in FIG. 13. In this case, due to the weight of the full bobbin 178c, the pole 101 bends at the position of the pin 103 as shown in the drawing and the end of the pole 101 comes in contact with the inside wall of the bobbin of the full bobbin 178c due to the force by the spring 104. Removal of the full bobbin 178c from the pole 101 is carried out at the stage of the returning movement of the slide base 156 from the position Y to X. During the movement of the connector 110 over the distance E, at the very moment of the disengagement of the top of the pole 101 from the full bobbin 178c, the pole 101 with the collar 108 is forced by the helical spring 114 to perform its returning movement. By this returning movement, the collar 108 comes again in contact with the stopper 109 via the cut-out surface 116.

Structure and operation of the mechanism for effecting the returning movement of the connector 110 and those of the bracket 126 will now be explained in more detail with reference to FIGS. 21 to 23. In the drawing, it is shown that the connector 110 is rotatably accommodated within a cylindrical body 140, which is formed in one body with the bracket 126, via needle bearings 139. The upper part of the bracket 126 is integrally connected with the arm 125 of the rack 170 by a cylindrical part 124. The arm 125 bears the load by the bracket 126 and the connector 110.

The solenoid 122 is fixed on the bracket 126 in a horizontal arrangement and the movable core 123 thereof is connected at its end to a horizontal link 127 via a pin 130. This horizontal link 127 is further connected to a vertical link 128 via a pin 129. This vertical link 128 is pivoted at its lower end to a pin 131 disposed transversely through the bracket 126. When electric voltage is applied to the solenoid 122, the movable core 123 slides in the horizontal direction and, when the core 123 arrives at the position designated as 123a, the links 127 and 128 assume the respective positions designated as 127a and 128a.

When the solenoid 122 is kept in inoperative condition, a spring 133, which is hooked at one end on a pin 132, is placed into an engagement with the lower end of the vertical link 128 via an engaging member 134 and, thereby, the elements 123, 127 and 128 assume

the dispositions shown with solid lines in the drawing FIG. 21. A pawl 137 formed on the lower end of the vertical link 128 is in a meshing engagement with a cut-out 1102, which is formed by cut-out faces 146 and 147 of a stopper 135 fixed to the connector 110 by a set screw 136. The relative position of the stopper 135 with respect to the connector 110 is so settled that the side face of the pawl 137 contacts the cut-out face 147. In this disposition, the cylindrical body 140 is in contact with the stopper 135 at the position 1103. In order to keep this disposition and to keep the pole 101 in the upright condition, a helical spring 141 is inserted over the end part of the connector 110. The outer end of the spring 141 is fixed to the side wall of the cylindrical body 140 while the inner end thereof is fixed to the side wall of a collar 142 which is securely mounted over the connector 110 by a pin 143. That is, the connector 110 is rotatably carried on both its ends by the cylindrical body 140 of the bracket 126 via the needle bearing 139. Reverse turning of the connector 110 is assured by two helical springs 141 inserted over the cylindrical body 140. The stopper 135 can be placed in the contact engagement with the cylindrical body 140 via the respective cut-out faces. When there is no application of external forces, the cut-out faces of the cylindrical body 140 and the stopper 135 are placed in a pressure contact to each other due to the urging force by the spring 141 at the position 1103, and the pawl 137 comes into engagement with the cut-out face 147 of the cut-out 1102 formed on the other side of the stopper 135. In this disposition, the collar 108 is so maintained that the pole 101 is in the upright condition.

The above-described combination of the bracket 126 with the connector 110 operates in the following manner. At the first-staged tilting of the full bobbin 178, the turning of the connector 110 is hindered by the engagement of the cut-out face 147 of the stopper 135 with the side face of the pawl 137 of the vertical link 128. Therefore, the first-staged tilting of the bobbin 178 is effected only by the turning of the collar 108 with respect to the connector 110. This movement comes to an end when the cut-out surface 117 of the collar 108 comes into pressure contact with the cushion rubber 118 of the stopper 109. Resistance against the moment by this turning generates at the engaging part of the pawl 137 of the vertical link 128 with the cut-out face 147 of the stopper 135.

Next, the full bobbin 178b must be received in the storing mechanism 183. The electro-magnetic clutch 166 is disconnected by the depression of the micro-switch (not shown) at the moment when the axis of the connector 110 arrived at a position right above the axis of one of the sprockets 182 positioned on one side of the storing mechanism 183. By this disconnection of the clutch 166, the connector 110 stops its horizontal movement and, simultaneously, a similar electric signal excites the solenoids 122 on both sides of the connector 110. By this excitement of the solenoid 122, the vertical link 128 is momentarily displaced to the position designated with 128a in FIG. 21 (chain and dott lines) and, simultaneously, the engagement of the pawl 137 with the cut-out face 147 of the stopper 135 is cancelled. Then, the full bobbin 178b further is inclined to the second-staged tilting position by momentarily turning the connector 110, the force by the spring 141 being overcome by the weight of the bobbin 178b. In this way, the full bobbin 178c is received horizontally

in the storing mechanism 183 as shown in FIGS. 13 and 15. That is, the bobbins 178c are accommodated in fine order by the bobbin receivers 180 and 180a.

Next, explanation will be given to the structure and operation of a cage 55 for accommodating the full bobbin 59a with reference to the illustration in FIG. 1. This cage 55 is removably encased within the box shaped space defined by the framework 54. For the cage 55 insertion into and removal from the framework 54, a plurality of horizontal shafts 71 are arranged on the bottoms of the framework 54, and multiple conveyer rollers 69 are rotatably mounted on the horizontal shafts at 71 at both inside bottoms of the framework 54. At each inside bottom of the framework 54, these rollers 69 are encircled by a belt conveyer 70 of narrow width which is sufficient to support one of the rail-shaped legs 84 of the cage 55. In order to circulate each belt conveyer 70, at outermost roller 66 is connected for driving to a drive motor 67 via sprocket 66 and a drive chain 68 as will be seen by referring to FIG. 2. The motor 67 is accompanied with a suitable reduction gear arrangement.

Accommodation of the full bobbins 59a into the cage 55 is practiced after the cage 55 is placed in position on the belt conveyer 70. In this accommodation, the cage 55 supports only both end parts of the full bobbins 59a which are arranged in several horizontal rows vertically superposed to each other. For this purpose, the following arrangement is employed in the shown embodiment. Four rotary shafts 85 are disposed on four corners of the cage 55 along the length of the latter, and sprockets 86 are securely mounted onto both ends of the shafts 85. Four sets of flexible continuous bodies 58 are disposed vertically encircling the sprockets 86. Mutually facing sides of the bodies 58 are provided with a plurality of rail-shaped supporting members 57 with equally spaced vertical distances between themselves. After the uppermost set of the supporting members 57 become full of bobbins 59, all the bodies 58 are moved together over a prescribed distance intermittently, thereby the next set of the supporting members 57 come into the position to accommodate the full bobbins 59. By repetition of the above-described intermittent travel of the bodies 58, full bobbins 59 are accommodated within the cage 55 in vertically spaced rows. In order to accommodate as many bobbins as possible, it is desirable that, in the respective rows, the bobbins are arranged in a zig-zag style. When larger capacity of the cage 55 is desired, it is employable also that, as shown in FIG. 2, the belt conveyer 70 is moved in both directions in accordance with the timing of the doffing operation and, thereby, the cage 55 is moved from the position B—B to the position A—A and vice versa.

The mode of bobbins accommodation according to the present invention will now be explained in detail, reference being made to FIGS. 24 to 30. As shown in FIG. 24, full bobbins 201a, 201b, 201c, etc. are fed into a bobbin storing mechanism 218 by a suitable bobbin transferring mechanism as previously described in such a manner that they are arranged in multiple rows vertically spaced from each other. The axial directions of the bobbins cross the longitudinal direction of rails 202 and 202a, and both ends 230 and 230a are supported by the rails 202 and 202a. In order to prevent possible rolling movement of the bobbins on the rails, the rails 202 and 202a may desirably be provided with members stably receptive of the bobbins placed thereon. For ex-

ample, receiver segments 231 such as shown in FIG. 25 can favourably be disposed at constant intervals onto the rails 202 and 202a, the receiver segments having recesses receptive of ends 230 or 230a of the bobbins 201. Bearing blocks 213 are disposed to eight corners of the cop storing mechanism 218 in order to carry horizontal shafts 207 and 212 rotatably. The shafts 207 and 212 are accompanied with sprockets 208 securely mounted to both ends of the shafts near the bearing blocks 213. In engagement with the sprockets 208, vertically running endless chains 216 are disposed to the mechanism 218. The above-described rails 202, 203, 204, 205, 206 and so on are disposed to the endless chains 216 being equally spaced from each other so that the rails can be moved together in the vertical direction by the circulation of the chains 216.

In order to move the pair of rails, for example a pair composed of the rails 202 and 202a, the horizontal shafts 207 and 207a are provided at their ends with sprockets 220 and 220a, respectively. Separately from this, shafts 241 and 241a are rotatably mounted onto the framework of the bobbin storing mechanism 218, carrying sprockets 223 and 223a, respectively. The sprockets 220 and 220a are connected for rotation to the sprockets 223 and 223a by chains 221 and 221a, respectively. Further, concentrically with the sprockets 223 and 223a, gears 222 and 222a are rotatably mounted onto the shafts 241 and 241a, respectively. The gears 222 and 222a are so arranged that they are placed in a peripheral meshing engagement with each other. In this way, both shafts 207 and 207a are connected to each other for a simultaneous rotation thereof, i.e. the simultaneous circulation of the endless chains 216 on both sides of the bobbin storing mechanism 218. By the above-described mechanism, the pairs of rails, e.g. rails 202 and 202a, can be moved simultaneously in the vertical direction while upholding the bobbins 201a and so on in horizontal disposition.

The vertical movement of the rails and the stop thereof at prescribed positions are effected in the following manner. In FIG. 24, one of the mutually meshing gears 222 and 222a, e.g. the gear 222, is placed in a meshing engagement with an output gear 224 of a reduction mechanism 228, whose input pulley 225 is driven for rotation by an output pulley 226 of a drive motor 229 via a belt 227.

The bobbin storing mechanism 218 of the above-described structure operates in the following manner. In the condition that the mechanism 218 is still empty, the drive motor 229 is started, the gears 222 and 222a are driven for rotation via the elements 226, 227, 225, 228 and 224 and the rails 202, 202a and so on are moved vertically until a certain pair of rails, e.g. the rails 205 and 205a, arrive at the uppermost position in the mechanism 218. In this disposition, by the operation of the separately arranged bobbin transferring mechanism as previously described, multiple bobbins 243a, 243b, 243c and so on are received in the receiver segments 231 of the rails 205 and 205a (see FIGS. 25 and 26) in the horizontal disposition. After the above-described operation is completed, the drive motor 229 is again energized for running and the chains 216 are moved vertically over the distance corresponding to the vertical spacing between vertically neighbouring pairs of rails so that the pair of rails 205 and 205a lower to the second highest position in the bobbin storing mechanism 218.

In order to carry out this limited lowering of the rails successfully, the following consideration should be employed in the design of the structure. The gear ratios between the sprockets 208, 220 and 223 are so selected that one complete revolution of the gears 222 and 222a results in the one step lowering of the rails 205 and 205a. When the gear ratios are fixed in this sense, the lowering of the rails can be stopped at prescribed positions by accompanying the gears 222 and 222a with suitable micro-switches (not shown). With lowering of the first set of rails 205 and 205a to the second highest position, the second set of rails, e.g. rails come to the uppermost position in the structure of the bobbin storing mechanism 218. Accommodation of the full bobbins in the bobbin storing mechanism is further carried on by repeating the above-described unit cycle of operation. In the disposition shown in FIG. 24, four sets of rails are full of bobbins in the bobbin storing mechanism 218.

In order to bring about a lighter and more compact structure of the bobbin storing mechanism 218, some special consideration must be paid for depositing the bobbins in a more dense mode within the mechanism 218. One typical example of such consideration is shown in FIG. 26, wherein the axial positions of the bobbins in a certain horizontal row are offset to the axial positions of the bobbins in the neighbouring rows over distance corresponding to half of the distance between the spindles. In other words, the bobbins are arranged in a vertically zig-zag disposition.

Next, explanation will be given of the system of taking out the bobbins from the bobbin storing mechanism 218. In FIG. 27, a bobbin taking out mechanism 242 is provided with a flat overhead surface on which the bobbin storing mechanism 218 can be mounted stably. On the lower side of the interior of the taking-out mechanism 242, a pair of bases 253 and 253a of a strong structure are arranged along the longitudinal direction of the mechanism 242. A plurality of bearing blocks 250 and 250a are secured on the bases 253 and 253a leaving adequate distances between them, respectively. These bearing blocks 250 and 250a respectively support shafts 249a and 249b rotatably, and each of the shafts carries a pair of pulleys 248 and 248a securely mounted thereon. Endless flexible bodies 247 and 247a are carried in tensioned condition by the pulleys 248 and 248a, respectively. The circular length of the flexible bodies almost doubles the length of the bobbin storing mechanism 218 and is so designed that all the bobbins 244a, 244b, 244c and so on in a certain row can be fully received on the upper surface thereof. In this way, the flexible bodies play the role of the intermittent conveyer of the bobbins taken out from the bobbin storing mechanism 218.

The mechanism for receiving the bobbins in the above-explained operation is constructed as follows. Referring to FIGS. 26 and 27, a plurality of bobbin supporters 246a, 246b, 246c and so on are fixedly mounted onto the endless flexible bodies 247 and 247a at constant intervals equal to the distance between the bobbins upheld within the mechanism 218, the flexible bodies 247 and 247a running over the pulleys 248 and 248a, respectively. In order to carry out the driving of the above-described flexible bodies 247 and 247a, a sprocket 251 is fixed to one end portion of the shaft 249a, which sprocket is connected to a suitable driving source (not shown) via a suitable chain. By rotation of

the shaft 249a so caused, the endless conveyer made up of the endless flexible bodies 247 and 247a is driven for circulation via the pulleys 248 and 248a.

The operation of the above-described bobbin taking-out mechanism 242 is as follows. In the first place, the bobbin storing mechanism 218 full of the bobbins is placed in position on the bobbin taking-out mechanism 242 as shown in the drawing. In order to carry out this motion smoothly, it is desirable to provide the upper face of the bobbin taking-out mechanism 242 with a suitable roll conveyer composed of rotary rollers, on which the bobbin storing mechanism 218 can be slidably mounted. After the bobbin storing mechanism 218 is registered at the prescribed position in this way, the endless conveyer made up of the endless flexible bodies 247 and 247a is driven for circulation via the sprocket 251. By this circulation of the endless conveyer, the bobbin supporters 246a, 246b, 246c and so on are brought to the positions just under the corresponding full cops 244a, 244b, 244c and so on respectively. This circulation of the endless conveyer over the limited length of distance can be controlled by accompanying the bobbin storing mechanism or the bobbin taking-out mechanism with suitably positioned micro-switch or switches (not shown). Next, the drive motor 229 is energized for rotation so that the rails of the bobbin storing mechanism 218 lower over one unit distance and the bobbins 244a, 244b, 244c and so on of the lowermost row are released from the support by the rails 206 and 206a. (see FIG. 27) By this cancellation of the support by the rails, the bobbins fall down into the bobbin taking-out mechanism 242 and are received by the bobbin supporters 246a, 246b, 246c and so on. The bobbins received are designated as 245a, 245b, 245c and so on in FIG. 26. After the bobbins are completely received in the bobbin supporters, the endless flexible bodies 247 and 247a are again driven for circulation and the bobbins so upheld by the endless conveyer are taken out of the bobbin taking-out mechanism 242. In order to carry out the above-described bobbins delivering action very smoothly, it is desirable that suitable guide plates for guiding the falling of bobbins into the bobbin taking-out mechanism 242 should be disposed over the bobbin taking-out mechanism 242. It is further desirable that the combined structure of the both mechanisms 218 and 242 should be so designed as to result in a short falling path for the bobbins.

In connection with the arrangement of the above-described structure, it is also possible that the drive motor 229 is rotated in the direction opposite to that in the foregoing description, the rails are moved upwardly towards the upper opening of the bobbin storing mechanism 218 and the bobbins may be taken out from the underside of the bobbin storing mechanism 218.

Next, explanation will be given of the manner of accommodating the bobbins in the zig-zag disposition within a bobbin storage cage in the process of the present invention, reference being made to the illustrations in FIGS. 28 and 30. Receiving of the bobbins into a bobbin storage cage 318 after the doffing operation is carried out within the region designated with R in the drawing. In the present case, 6 bobbins are doffed simultaneously. In contrast to this, the bobbin storing cage 318 has a length which is capable of accommodating 12 bobbins in side by side alignment along the longitudinal direction of the cage. Further, the bobbins can be accommodated in 6 vertical rows in the cage

318, that is, 72 bobbins can be accommodated together within one cage 318.

In the operation, the cage 318 accommodates six bobbins 301a, 301b, 301c and so on simultaneously while it is in the condition designated with 318a in the drawing. That is, the bobbin storing cage 318 stands at the position designated with B-B in the illustration. Next, by a limited circulation of a belt 349, the cage travels leftwards in FIG. 28 over the distance A in FIG. 30 and comes to the position designated with A-A in the illustration. In this position, the cage 318 accommodates the next six bobbins on its bobbin receivers 331.

This operational sequence is now explained in more detail with reference to the illustration in FIG. 30, wherein the condition during the bobbin accommodation within the cage 318 is seen from the right side in the illustration in FIG. 1. With the progression of the doffing operation, an increased number of bobbins are accommodated within the cage as shown in the drawing. In the illustration, accommodation of the bobbins is carried out in the region designated with R.

In the first-stage doffing I, the cage moves leftward and the bobbins are accommodated by the six bobbin receivers on the right half of the cage. Next, in the second-staged doffing II, the cage travels rightwards over the distance A and the next set of bobbins are accommodated by the different six bobbin receivers on the left half of the cage. In this way, 12 bobbins are accommodated in the first row in the cage. Next, the rails lower over one unit distance and bobbin receivers 331-2 in the next row come in the turn. In the subsequent third-staged doffing III, the cage in this condition is moved leftwards over the distance B so that the bobbin receivers 331-2 is engaged in the accommodation of the bobbins. In this connection, however, the difference between the travelling distances A and B is equal to the half of the bobbin diameter, thereby the bobbins are accommodated in the cage in the zig-zag disposition. In the fourth-staged doffing IV, the cage is moved rightwards over the distance A and the bobbin receivers 381-2a are engaged in the accommodation of the bobbins. By the foregoing operation, 24 bobbins are already accommodated in the cage in two rows. Next, the rails lower over the one unit distance and the bobbin receivers 381-3 now come to the uppermost position in the cage. After the cage is moved leftwards over the distance C, the fifth-staged doffing V of the bobbins onto the receivers 381-3 is carried out. In this case, the length of the distance C needs to be larger than the distance A by half of the bobbin diameter. The fifth-staged bobbin accommodation V is carried out in the disposition the same as that in the first-staged bobbin accommodation I. In the foregoing process, the cage is moved horizontally over the distances in the order of A, B, A and C and the rails are lowered over one unit distance once in every two doffing operations, thereby the bobbins can be densely accommodated in rows in the cage. The above-described sequential operation is electrically controlled by the control device 361 shown in FIG. 28.

The mechanism for steering the horizontal movement of the cage 318 is shown in FIG. 29, wherein shafts 352 are arranged for rotation in the cage 318 across the longitudinal direction of the cage, each shaft being provided with rollers 351 fixedly mounted on both ends thereof. Two sets of mutually parallel flexible

endless bodies 349 and 349a run in the longitudinal direction of the cage 318 passing over the rollers 351 and the cage 318 is placed on the flexible bodies. Usually, the flexible bodies are given in the form of flat endless belts. One of the shafts 352 is provided with a sprocket 350 fixedly mounted thereon at a position outside the roller 351 and the sprocket 350 is connected for rotation to another sprocket 357 via a chain 356, the sprocket 357 being fixedly mounted onto the output shaft of a reduction motor 358. The reduction motor 358 is mounted on a base 359 placed on the framework 332 of the cage 318. By shifting the phase of the electric voltage to be applied to the reduction motor 358, the travelling direction of the flexible bodies 349 and 349a can be shifted as desired. Further, in order to provide the flexible bodies with necessary tension during the operation, one of the outermost shafts 352a is provided with a boss 360 disposed to the middle thereof and a bolt 353 integrally connected thereto is engaged with a fixed link 354 on the framework 332 via nuts 355. Tension of the flexible bodies can be adjusted by adjusting the engagement of the bolt 353 with the link 354 by the nuts 355.

Next explanation will be given of the structure and operation of the empty bobbin feeding mechanism in reference to the illustrations in FIGS. 1 and 2. As shown in the drawings, empty bobbins 1 are encased in vertical disposition within a container 4 at positions corresponding to the positions of the spindles 73 on the draw-twister. The container 4 is detachably mounted on beams 21 and 22 over a framework 15 which is placed on the movable base 40. In order to maintain the vertical disposition of the empty bobbins 1 in the container 4, the width of the container 4 is made almost the same as the diameter of the bobbins 1, the containers 4 are mounted in somewhat inclined disposition and a suitable pressor mechanism 2 is disposed on the back-side of the containers 4. The pressor mechanism 2 is so disposed that it always presses the empty bobbins from back side due to the rolling tendency of wheels 3 attached thereto. The respective containers 4 are accompanied with shutters 6 disposed on the front side thereof and the shutters 6 are provided with pawls 6a, 6b, 6c and 6d for feeding the empty bobbins 1a into fixed chutes 5. The shutters 6 are connected to each other and are mounted on a rail 9 via multiple wheels 20. They can be automatically moved together in the longitudinal direction reciprocally by the shifting action of a pressure valve (not shown) of an air cylinder 24. In this case for example, when the shutters 6 are moved rightwards in FIG. 2 over a prescribed distance, the pawls 6c and 6d open so that the empty bobbins in the foremost row are issued into the fixed chutes 5, whereas the pawls 6a and 6b close so that the empty bobbins in the subsequent rows are restrained from being issued into the chutes 5.

The empty bobbins so issued into the chutes 5 then fall down into movable chutes 7 until they arrive at the position of the gates 16 displaceably located at the lower end of the movable chute 7 so as to open or close the bottom aperture of the chute 7. A solenoid 28 is secured to the movable plate 27 in such a way that an end of a solenoid plunger 28a is connected to the gate 16. Consequently, when the solenoid 28 is excited and the solenoid plunger 28a is retracted, the gate 16 is displaced from the bottom aperture of the chute 7 so that the chute 7 is opened. The movable chutes 7 are

fixed to the front face of a movable plate 27 which is carried by a pair of sliding brackets 25 in a slideable arrangement along vertical shafts 19. The vertical shafts 19 are fixed at its upper end to a bracket 23 fixed to the framework 15 and at its lower end to the foot part of the framework 15. The shafts are disposed in somewhat inclined disposition in order to bring about a good registration of the gates 16 at the tops of the spindles 73.

In order to control the vertical movement of the movable plate 27, the plate 27 is carried by ropes 12 at the portion of the sliding brackets 25 and the other ends of the ropes 12 are connected to air cylinders 14 via guide rolls 10, 11 and 13. The stroke of the air cylinder 14 causes a corresponding up and down movement of the movable plate 27.

When the empty bobbins 1a are to be inserted over the spindles 73, the arms 29 and 30 are turned into the almost upright disposition so that there should be no interference between the motions of the movable plate 27 and the gripper chucks 36. After the movable base 40 has completed its forward movement, the air cylinders 14 cause lowering movement of the movable plate 27 and, thereby, the movable chutes 7 are lowered to the vicinity of the tops of the spindles 73. A switch (not shown) is disposed at a position where the downward motion of the movable chutes 7 is terminated, consequently, upon contacting the lower end of the chute 7 with the above-mentioned switch, the solenoid 28 is electrically excited in order to make the gates 16 open. By this opening of the gates 16, empty bobbins 1a contained within the fixed chutes 7 fall down due to their own weight and are inserted over the corresponding spindles 73.

In order to effect a reliable insertion of the bobbins over the spindles in the present invention, air cylinders 17 located behind the respective gates 16 are momentarily made operative and the empty bobbins 1a which are reserved in the chutes are suitably pressed towards the spindles 73 by a turning movement of pushers 8. After the pushers 8 resume their original disposition and the gates 16 are automatically closed by springs (not shown), the movable chutes 7 are lifted by the operation of the air cylinders 14 and the supply operation of the empty bobbins to the spindles is completed. The above-described structure of the mechanism for effecting the vertical movement of the movable chutes is accompanied with such advantages as simplicity in the construction and excellent and exact registability of the bobbins at the corresponding spindles.

As is clear from the foregoing description, in the structure of the apparatus of the present invention, the movable base 40 is mounted for horizontal movement on the movable framework. On this movable base 40, there is mounted the doffing mechanism mainly comprised of the swingable arms 29 and 30, the empty bobbin feeding mechanism having the movable chutes 7, the bobbin transerrer controlling the movement of the poles 51 located under the movable base 40 and the cage 55 for accommodating the full bobbins contained within the framework 54. In order to control the sequential operations of these elements, the apparatus is provided with a control panel 26. It is desirable, in this connection, that the control panel 26 is usable for both the automatic and manual control of the entire system.

Next, the operational sequence of the apparatus of the present invention will be explained in more detail, reference being made to FIGS. 3 to 12.

In the first place, as shown in FIG. 3, the framework 54 advances to the prescribed position in order to doff the full bobbins 59b resting on the spindles 73. In this stage of the operation, the movable base 40 is still retained in its receded position and the poles 51 are held by the movable arm 48 resting in the advanced position.

Next, as shown in FIG. 4, the movable base 40 moves to the advanced position and, simultaneously, the movable arm 48 moves to its receded position. In this connection, a big cut-out 76 is formed on the front side center part of the movable base 40 so that the movement of the poles 51 is not interfered with by the presence of the movable base 40. (see FIGS. 1 and 2)

In the stage shown in FIG. 5, the arms 29 and 30 tilt forwardly until the gripper chucks 36 firmly grasp the tops of the corresponding full bobbins. After the bobbins are completely grasped, the arms 29 and 30 turns rearwardly so as to disengage the bobbins 59b from the corresponding spindles 73 and the bobbins so disengaged are brought to the position designated with 59a in FIG. 6.

After the bobbins are placed in this position, the movable base 40 recedes over the prescribed distance and the movable arm 48 advances simultaneously. (see FIG. 7)

Next, the arms 29 and 30 again tilt forwardly until the bobbins are inserted over the corresponding poles 51 as designated with 59c in the drawing and the full bobbins 59c so inserted are released from the grasp by the corresponding gripper chucks 36 as shown in FIG. 8.

When the arms 29 and 30 return to their upright position as shown in FIG. 9, the full bobbins with the poles 51 tilt towards the inside of the framework 54 due to their own weight and are maintained at the position designated with 59d by stoppers 53 (see FIG. 2). In this tilting, the tops of the full bobbins pass through the cut-out 76 of the movable base 40.

Next, as shown in FIG. 10, both the movable base 40 and the movable arm 48 perform their advancing and receding movements, respectively. By these movements, the empty bobbin feeding mechanism 87 on the movable base 40 is brought to the position to feed empty bobbins and the full bobbins 59d are brought to the position corresponding to the bobbin storing cage 55. Next, solenoids 50, which are disposed on brackets 49 for rotatably supporting the both ends of the rod 52, is energized in order to cancel the restriction on the rotating tendency of the rod 52 by a stopper (not shown). Due to this cancellation of the restriction, the rod 52, the poles 51 and the full bobbins 59d further tilt simultaneously by the own weight of the bobbins until the bobbins are received horizontally by the supporting members 57 in the uppermost position in the cage 55 as designated with 59e in FIG. 11. Concurrently with this, through the lowering movement of the movable chutes 7 empty bobbins 1c are fed to the spindles 73. After the empty bobbins 1c are completely fed to the spindles 73 as shown in FIG. 12, the movable chutes 7 are returned to their lifted position and one complete cycle operation of the apparatus comes to an end.

In practical operation, only the movement of the cage 55 is started while keeping the other elements in the condition shown in FIG. 12, and the tilting move-

ment of the arms 29 and 30 is followed thereafter in order to carry out the next cycle of doffing operation. Therefore, disengagement of the full bobbins 59e from the poles 51a is carried out at the stage of the receding movement of the movable base 40 after the doffing operation in the subsequent cycle. Right after this disengagement, the horizontal movement of the cage 55 or the lowering movement of the supporting members 57 for the subsequent accommodation of the new full bobbins begins.

Further, at the moment when the movable arm 48 has advanced and the poles 51a are disengaged from the corresponding bobbins 59e resting within the cage 55, the rod 52 is returned to its initial position by a helical spring (not shown) which is disposed to the engaging part of the bracket 49 with the rod 52. Simultaneously with this, the poles 51 on the rod 52 are returned to the position whereupon the abutment of the boss 80 of the pole 51 comes in contact with the abutment of the stopper 53, i.e. to the upright disposition.

As is clear from the foregoing description, according to the system of the present invention, a plurality of full bobbins can be simultaneously doffed and they can be accommodated within the storing cage in right order without damaging the yarns on the bobbins. Concurrently with this doffing operation, feeding of new empty bobbins to the spindles can be carried out, resulting in shortening of the time necessary for the doffing and feeding operations. For example, when the system of the present invention is employed, one cycle operation can be completed within 10 to 15 seconds.

It should be understood, in addition, that various modifications can be derived from the above-explained basic structural features of the present invention. For example, the movable base 40 and the movable arm 48 may be driven by separate drive sources, turning of the rod 52 may be caused by any suitable compulsory drive mechanism other than by the weight of the bobbins and only the movable chutes 7 may be disposed on the movable base 40 while the container 4 and the fixed chutes 5 are mounted on a suitable structure fixed on the frame work 54.

As one of the employable modifications, it is desirable to accompany the poles 51 with suitable guide mechanism so as to smooth the insertion of the full bobbins over the poles. One of the embodiment of this sense is illustrated in FIGS. 32A to 32C. A guide 510 is disposed to the outer end of the rod of an air cylinder 511, one typical embodiment of the guide 510 being illustrated in FIG. 33. The guide 510 shown in FIG. 33 is of a panel shape whose inside surfaces covers downwardly so that the bobbin passing therethrough can be smoothly and reliably guided towards the corresponding pole.

In the disposition shown in FIG. 32A, a bobbin 503 is grasped at its top by a gripper chuck 505 and the guide 510 is still located under the corresponding peg 509.

Next, an arm 507 is turned about a pivot 508 for the doffing action and the guide 510 is now brought to a position above the peg 509 by the stroke of the air cylinder 511.

In this disposition, the pivot 508 is receded to the position shown in FIG. 32C and the arm 507 is further turned to a position whereupon the bobbin 503 is hung in vertical condition. In this condition, the lower end of

the bobbin 503 is guided towards the peg 509 through contact with the guide 510. As soon as the lower end of the bobbin is inserted over the peg 509, the air cylinder 511 comes in operation so that the guide 510 is brought under the peg 509. By this timely operation, the guide 510 is free from contact with waste yarns and, thereby, undesirable damage on the yarn can be effectively prevented.

The other modification of the apparatus of the present invention is shown in FIG. 31. In order to mitigate the yarn breakage caused by accidental winding of the yarn 401 around the bobbin 406 and/or the spindle when the yarn is slackened, it is recommended to eject a suitable jet air stream towards the cop at the time of doffing. For this purpose, in the structure shown in FIG. 31, the gripper chuck 412 is accompanied with an air ejection nozzle 415 so that compressed air can be ejected when the chuck approaches the top of the spindle. This ejection of the compressed air is effective at the time of the empty bobbin insertion over the spindle also.

What is claimed is:

1. Method for doffing full bobbins on an apparatus which travels along the rows of spindles of drawtwisters and is provided with a doffing mechanism, a bobbin transerrer, a bobbin storing mechanism and an empty bobbin feeding mechanism comprising, in the following operational sequence: advancing said doffing mechanism from its stand-by position towards the row of full bobbins resting on said spindles; extracting said multiple full bobbins simultaneously off from said spindles by said doffing mechanism; withdrawing said doffing mechanism with said full bobbins from said row of spindles; transferring said full bobbins carried by said doffing mechanism onto poles of said bobbin transerrer whereby said full bobbins are supported by insertion of the respective poles into an axial hollow of each bobbin wherein said full bobbins are at first received by said poles in a substantially upright disposition and said poles are then tilted so as to hold said bobbins in a substantially horizontal disposition and; transferring said full bobbins from said poles to said bobbin storing chamber all without the physical contact of the mechanisms with the filament yarn of said full bobbins.

2. Apparatus for doffing full bobbins on textile machines such as draw-twisters comprising in combination: a cage for storing full bobbins encased within a framework travelling along the row of spindles on said draw-twister; a movable base disposed on said framework in an arrangement movable to and from said row of spindles; a doffing mechanism disposed on said movable base and provided with a plurality of gripper chucks corresponding to said spindles including means for moving said gripper chucks into engagement with full bobbins on said spindles to remove the same therefrom and a bobbin transerrer movable to and from said row of spindles, in relation to said movement of said movable base wherein the moving directions of said movable base and said bobbin transerrer during simultaneous operation of both are opposite to each other and provided with multiple tiltable poles corresponding to said gripper chucks for receiving the full bobbins from said gripper chucks for transfer to said storing cage, said bobbin transerrer being positioned between said movable base and said bobbin storing cage on said framework.

3. Apparatus for doffing full bobbins on textile machines such as draw-twisters comprising in combination: a cage for storing full bobbins encased within a framework travelling along the row of spindles on said draw-twister; a movable base disposed on said framework in an arrangement movable to and from said row of spindles; a doffing mechanism disposed on said movable base and provided with a plurality of gripper chucks corresponding to said spindles including means for moving said gripper chucks into engagement with full bobbins on said spindles to remove the same therefrom and; a bobbin transerrer movable to and from said row of spindles in relation to said movement of said movable base and provided with multiple tilttable poles corresponding to said gripper chucks for receiving the full bobbins from said gripper chucks for transfer to said storing cage wherein said poles are capable of folding at a joint therein, said bobbin transerrer being positioned between said movable base and said bobbin storing cage on said framework.

4. Apparatus for doffing full bobbins on textile machines such as draw-twisters comprising in combination: a cage for storing full bobbins encased within a framework travelling along the row of spindles on said draw-twister having multiple pairs of rails for supporting both ends of said full bobbins mounted superposedly within said cage in a vertically movable arrangement; a movable base disposed on said framework in an arrangement movable to and from said row of spindles; a doffing mechanism disposed on said movable base and provided with a plurality of gripper chucks corresponding to said spindles including means for moving said gripper chucks into engagement with full bobbins on said spindles to remove the same therefrom and a bobbin transerrer movable to and from said row of spindles, in relation to said movement of said movable base and provided with multiple tilttable poles corresponding to said gripper chucks for receiving the full bobbins from said gripper chucks for transfer to said storing cage, said bobbin transerrer being positioned between said movable base and said bobbin storing cage on said framework.

5. Apparatus for doffing full bobbins on textile machines such as draw-twisters comprising in combination: a cage for storing full bobbins encased within a framework travelling along the row of spindles on said draw-twister a movable base disposed on said framework in an arrangement movable to and from said row of spindles; a doffing mechanism disposed on said movable base and provided with a plurality of gripper chucks corresponding to said spindles including means for moving said gripper chucks into engagement with full bobbins on said spindles to remove the same therefrom a bobbin transerrer movable to and from said row of spindles in relation to said movement of said

movable base and provided with multiple tilttable poles corresponding to said gripper chucks for receiving the full bobbins from said gripper chucks for transfer to said storing cage, said bobbin transerrer being positioned between said movable base and said bobbin storing cage on said framework and; an empty bobbin storing mechanism carried by said movable base and disposed above said doffing mechanism having slideable chutes which are movable at prescribed operational stages of said doffing mechanism and said bobbin transerrer and are slideable upward or downward along a guide member secured to said framework each of said chutes being further provided with a gate capable of opening or closing the bottom aperture thereof.

15 6. Method for doffing full bobbins on an apparatus which travels along the rows of spindles of draw twisters and is provided with a doffing mechanism, a bobbin transerrer, a bobbin storing mechanism and an empty bobbin feeding mechanism comprising, in the following operational sequence: advancing said doffing mechanism from its stand-by position towards the row of full bobbins resting on said spindles; extracting said multiple full bobbins simultaneously off from said spindles by said doffing mechanism; withdrawing said doffing mechanism with said full bobbins from said row of spindles transferring said full bobbins carried by said doffing mechanism onto poles of said bobbin transerrer whereby said full bobbins are supported by insertion of the respective poles into an axial hollow of each bobbin; transferring said full bobbins from said poles to said bobbin storing chamber all without the physical contact of the mechanisms with the filament yarn of said full bobbins and; tilting said full bobbins carried by said poles of said bobbin transerrer over a prescribed turning angle; making said bobbin transerrer recede from said row of spindles; accommodating said full bobbins within said bobbin storing mechanism, and; disengaging said poles of said bobbin transerrer from said full bobbins by advancing said bobbin transerrer towards said row of spindles.

20 7. Method as claimed in claim 6 wherein said full bobbins are at first received by said poles in a substantially upright disposition and said poles are then tilted so as to uphold said bobbins in a substantially horizontal disposition.

25 8. Method as claimed in claim 6 wherein said tilting of said poles is carried out in two stages.

9. Method as claimed in claim 6 wherein, concurrently with the operations quoted, empty bobbins are fed to said spindles by said empty bobbin feeding mechanism.

10. Method as claimed in claim 9 wherein feeding of said empty bobbins is carried out concurrently with the receding motion of said bobbin transerrer.
